United States Patent Office

Des. 212,220
Patented Sept. 17, 1968

212,220

FIREARM OR SIMILAR ARTICLE

Alfred H. Crouch, Santa Monica, Calif., and Paul A. La Violette, Jr., and Edward M. Marino, North Haven, Conn.; said La Violette and said Marino assignors to The High Standard Manufacturing Corporation, Hamden, Conn., a corporation of Connecticut

Filed Oct. 18, 1967, Ser. No. 9,034

Term of patent 14 years

(Cl. D22—6)

FIG. 3

FIG. 4

FIG. 5

FIG. 1 is a perspective view of a firearm or similar article, showing our novel design and looking from the right front side thereof;

FIG. 2 is a side elevation thereof, with the firearm tilted back at about 45° in order to expose the underside thereof;

FIG. 3 is another perspective view thereof, looking from the left front side;

FIG. 4 is a right-side view thereof; and

FIG. 5 is another perspective view thereof, looking from the right and rear.

We claim:

The ornamental design for a firearm or similar article, substantially as shown.
